(57) **CLAIM**

The ornamental design for an organ protection layer, as shown and described.

DESCRIPTION

FIG. 1 is a perspective view of one embodiment of an organ protection layer.

FIG. 2 is a top plan view of the organ protection layer of FIG. 1.

FIG. 3 is a bottom plan view of the organ protection layer of FIG. 1.

FIG. 4 is a right or left side elevation view of the organ protection layer of FIG. 1; and,

FIG. 5 is a front or rear elevation view of the organ protection layer of FIG. 1.

The central longitudinal line and the innermost oval circle in FIGS. 1-3 are shown in broken lines that do not form any part of the claimed design. For all other figures, the dashed lines illustrate a pattern of openings in the organ protection layer and form a part of the claimed design.
